VENDING MACHINE

Juddson B. Ryno, Chicago, and Charles L. Casey,
Riverside, Ill., assignors to Reliable Sheet Metal
Engineering Co., Chicago, Ill., a corporation of
Illinois

Application October 26, 1944, Serial No. 560,378

7 Claims. (Cl. 194—75)

1

This invention relates to improvements in vending machines of the coin-controlled type, and one of the objects of the same is to provide, in a machine of this character, improved means for ejecting the articles, and improved means for rendering the ejecting mechanism inactive in the absence of articles in the holder, which means will lock the ejector against operation while the actuating mechanism for the ejector remains active.

A further object is to provide improved means for closing the coin receiving opening, and improved means for controlling the actuation of said closing means.

To the attainment of these ends and the accomplishment of other new and useful objects as will appear, the invention consists in the features of novelty in substantially the construction, combination and arrangement of the several parts, hereinafter more fully described and claimed, and shown in the accompanying drawings illustrating this invention, in which

Fig. 1 is a perspective view of a machine of this character, constructed in accordance with the principles of this invention, and with the front plate removed.

Fig. 2 is a perspective view of the front plate of the machine.

Fig. 3 is a detail vertical, sectional view taken on line 3—3, Fig. 5.

Fig. 4 is a detail sectional view taken on line 4—4, Fig. 5, showing some of the parts in a different position from that shown in Fig. 3.

Fig. 5 is a detail horizontal, sectional view taken on line 5—5, Fig. 3.

Fig. 6 is a detail sectional view taken on line 6—6, Fig. 3.

Fig. 7 is a detail sectional view taken on line 7—7, Fig. 3.

Fig. 8 is a detail sectional view showing the manner of locking the ejector slide, by the follower, against return movement.

The machine consists, essentially, of an outer casing or housing 10, which may be of any desired size and configuration, and constructed of any suitable material, the front of the casing being open and provided with a removable closure 11 having an offset portion 12, in which latter is provided a coin receiving slot 13. The lower edge 14 of the lower portion 15 of the closure is adapted to be seated in a groove or channel 16, and at the upper end of the closure may be provided a suitable lock 17 which engages beneath a flange or portion 18, to removably secure the closure in position. The closure 55

2

is preferably provided with flanges 19 that extend behind the side walls of the casing.

Within the housing thus formed, is a removable supporting structure or frame comprising uprights 20, to form a receptacle or holder 21 for the articles to be vended, and this structure is shaped to form a platform 22, a portion of which forms the bottom of the holder 21. When in position, and when the closure 11 is in place, the platform 22 will be disposed beneath and spaced from the offset portion 12 of the closure.

Mounted to slide upon the platform 22, and between suitable guides 23, is an ejector 24, preferably in the form of a plate, having a slot 25 therein, and also being provided with an aperture or opening 26. At the forward end of the guides 23 is arranged an upright 27 having an opening 28 therethrough, in alignment with the slot 25 in the ejector. Supported by the upright 27 is a pocket 29, one wall of which is formed by the upright 27, and the other wall is provided with an opening 30 in alignment with the opening 28 in the upright 27. The entrance to the pocket 29 is in alignment with the coin receiving opening 13 in the front or closure 11 of the casing, so that when a coin is dropped into the opening 13, and the parts of the mechanism are in the proper position, the coin will drop into the pocket 29, and into an opening 31 in the platform 22. This opening 31 is of a size and shape that when a coin is dropped into the opening 31, it will not pass entirely therethrough, as shown more clearly in Fig. 7, but will be supported by the edges of the slot or opening 31, and by fingers or up-turned portions 32 on the ejector 24 on each side of the slot 25 in the ejector.

The numeral 33 designates an oscillatable shaft pivotally supported by the said frame, and removable therewith from the casing. Connected 40 to the shaft 33 for oscillation therewith, is an arm 34, one extremity 35 of which arm is positioned in front of the upright 27 in the normal position of the arm, as shown in Fig. 3, and is adapted to be moved by rocking the shaft 33 in the proper direction, by means of an operating handle 36, through the opening 30 in the wall of the pocket, and against the coin which is in the pocket. By a further movement of the operating handle 36 and, consequently, the extremity 35 of the arm, this extremity will be moved through the opening 30 in the front wall of the pocket, into engagement with the coin, and will force the coin, together with the ejector 24, forwardly, so that the edge of the ejector will contact with the edge of the lowermost article 36a

in the holder, to eject the latter so that it will be discharged, by means of a chute 37, to the delivery outlet 38 of the casing.

When the extremity 35 of the arm 34 first contacts the coin in the pocket, the coin and the extremity of the arm will be moved through the opening 28 in the front wall 27 in the pocket, and as the coin is forced against the upturned ends or fingers 32 of the ejector 24, the ejector will be advanced to eject the article. This advancement of the coin and ejector will cause the coin to be positioned so as to drop through an enlarged portion 39 of the slot 31 in the platform 22, into a receptacle 40. This receptacle is removably supported by means of suitable guides 41, and may be removed through the front of the machine when the closure 11 is removed, as will be clearly seen from Figs. 1 and 4 of the drawings.

As soon as the article has been ejected and the operating handle 36 is released, the shaft 33 and the arm 34 will be returned to their normal positions by means of the spring 42, one end of which spring is anchored to an arm 43 on the shaft 33, as at 44, and the other end of the spring is anchored to a fixed support 45 on the removable casing.

Thus it will be seen that by inserting a proper coin into the coin receiving opening 13, and by operating the shaft 33, the ejector may be moved forwardly and an article dispensed. As soon as the handle 36 is released, the spring 42 will serve to return the shaft and the arm 34 to their normal positions, and, in so doing, the extremity 35 of the arm will engage the rear end 46 (see Fig. 4) of the slot 25 in the ejector, to move the latter back to normal position.

Arranged within the holder 21, and supported by the supply of articles 36a, is a follower 47 which may be of any desired configuration, but is here shown as being formed of a channel bar which rests upon the article. A handle 48 may be connected to the follower, by means of which it may be removed and replaced in the holder 21. Carried by the follower 47, and loosely projecting therethrough, is a pin or member 49 that is freely removable with respect to the follower.

When the parts are in the position shown in Figs. 3 and 4, that is, when the holder 21 contains a supply of articles to be vended, the follower will rest upon the top of the supply, and as the pin or member 49 is loosely mounted upon the follower, it will assume the position with respect to the follower, as shown in Figs. 3 and 4. When, however, the follower reaches the bottom of the holder 21, and rests upon the last article 36a therein, the last article may be vended or delivered by the ejector, but as the ejector ejects the last article, it will be moved so that the opening 26 therein will be in alinement with the end of the pin 49 carried by the follower 47, so that the pin will enter thereinto, the wall of the opening 26 forming a shoulder behind which the pin engages. The pin will also enter an opening 50 in the platform 22, and thereby lock the ejector against return movement. However, when the parts are in this position, that is, when the ejector is locked against return movement, and when the operating handle 36 is released, the spring 42 will return the arm 34 and extremity 35 to a certain extent, which extent of return movement will be limited by the engagement of the extremity 35 of the arm 34 against the end 46 of the slot 25 in the ejector, and this will prevent the extremity from moving too far backwardly, so as to control a closure for the pocket

29, and thereby prevent the insertion of a coin into the pocket when the machine is empty.

The closure for the pocket 29 preferably consists of a pivotally mounted member 51, of any desired or suitable construction, the extremity 52 of which is movable into the position shown in Fig. 4, to prevent the insertion of a coin thereinto, and out of the position shown in Fig. 4 to the position shown in Fig. 3, to permit of the insertion of a coin thereinto. The normal position of the closure 51 is that shown in Fig. 3, and in dotted lines in Fig. 4. It will assume this position by reason of the fact that the end or extremity 35 of the arm 34, under the stress of the spring 42, will cause the parts to assume the positions shown in Fig. 3, so as to uncover the pocket. When, however, a proper coin is inserted, and the shaft 33 rocked in a clockwise direction, as shown in Fig. 3, the extremity 35 will move away from the closure 51 to the position shown in Fig. 4, and the closure will automatically assume the full-line position in such figure.

When the last article is ejected from the holder, and as the ejector will be locked against return, the extremity 35 of the arm 34 will also be locked against return, and will be prevented from moving the closure 51, so that the pocket 29 will be opened. If desired, a stop 52 may be provided to limit the opening movement of the closure 51.

All of the parts of the mechanism are mounted upon the frame, which is removable, as a unit, from the casing 10 by removing the closure 11. One of the side walls of the casing is provided with a suitable slot 53 for the reception of the shaft 33, and to permit the shaft to slide therethrough when the unit is removed from the casing.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. In a vending machine, an article holder, an ejector slide for ejecting the articles from the holder, an operating element for the slide, separate therefrom, a coin receiver, a shoulder on the slide behind which the coin will be positioned when inserted into said receiver, means for actuating said element, to cause the element to engage the coin and, through the medium of said coin, actuate the slide to eject an article, said element also operating to return the slide when the coin is discharged from said receiver, a follower in said holder, and a projection carried by said follower, adapted to engage behind a shoulder on the slide, in the absence of articles in the holder, for locking the slide against return movement, whereby the said element may be returned independently of the slide.

2. In a vending machine, an ejector slide, an actuating element separate from and operable independently of the slide, means for operating said element, a coin receiver, a shoulder on the slide behind which the coin is adapted to be positioned when in the receiver, to be engaged by said element upon movement of the latter in one direction, to move the slide to eject an article, and a closure for said receiver separate from said element and movable into and out of active posi-

tion with respect to the receiver, said closure being controlled in such movements by the operation of said element.

3. In a vending machine, an ejector slide, an actuating element separate from the slide, means for operating said element, a coin receiver, a shoulder on the slide behind which the coin is adapted to be positioned when in the receiver, to be engaged by said element upon movement of the latter in one direction, to move the slide to eject an article, and a pivotally mounted member movable into position to close and open said receiver, said closure being controlled in its movements by the movements of the said element.

4. In a vending machine, an ejector slide for the articles, an actuating element for moving the slide, said element being separate from said slide, an operating handle for moving the said element, a coin receiver, a shoulder on said slide behind which the coin is positioned when in said receiver, there being openings in the walls of said receiver through which said element is adapted to pass in the absence of a coin in the receiver, said element engaging a coin when present in the receiver, to shift said slide to move the latter in one direction, said coin being delivered automatically from said receiver, whereby the said element may be returned independently of the slide, and means for locking the slide against return movement.

5. In a vending machine, an ejector slide for the articles, an actuating element for moving the slide, said element being separate from said slide, an operating handle for moving the said element, a coin receiver, a shoulder on said slide behind which the coin is positioned when in said receiver, there being openings in the walls of said receiver through which said element is adapted to pass in the absence of a coin in the receiver, said element engaging a coin when present in the receiver, to shift said slide to move the latter in one direction, said coin being delivered automatically from said receiver, whereby the said element may be returned independently

of the slide, means for locking the slide against return movement, and means controlled in its operation by the actuation of said element, for closing and opening said coin receiver.

5. In a vending machine, an ejector slide for the articles, an actuating element for moving the slide, said element being separate from said slide, an operating handle for moving the said element, a coin receiver, a shoulder on said slide behind which the coin is positioned when in said receiver, there being openings in the walls of said receiver through which said element is adapted to pass in the absence of a coin in the receiver, said element engaging a coin when present in the receiver, to shift said slide to move the latter in one direction, said coin being delivered automatically from said receiver, whereby the said element may be returned independently of the slide, a holder for the articles, and a follower in the holder, the said slide and the said follower being provided, one with a projection and the other with a shoulder behind which the projection will engage, to lock the slide against return movement with the said element in the absence of articles in said holder.

15 6. In a vending machine, an ejector slide for the articles, an actuating element for moving the slide, said element being separate from said slide, an operating handle for moving the said element, a coin receiver, a shoulder on said slide behind which the coin is positioned when in said receiver, there being openings in the walls of said receiver through which said element is adapted to pass in the absence of a coin in the receiver, said element engaging a coin when present in the receiver, to shift said slide to move the latter in one direction, said coin being delivered automatically from said receiver, through the slide and into the machine, whereby the said element may be returned independently of the slide, and means for locking the slide against return movement.

JUDDSON B. RYNO.
CHARLES L. CASEY,
